UNITED STATES PATENT OFFICE

JAMES L. BREESE, JR., OF CHICAGO, ILLINOIS, ASSIGNOR TO OIL DEVICES CORPORATION, OF CHICAGO, ILLINOIS, A CORPORATION OF ILLINOIS

CONTROL MEANS FOR HYDROCARBON BURNERS

Application filed November 17, 1927. Serial No. 233,786.

My invention relates to a fuel control for use with a hydrocarbon burner and has for a particular purpose the provision of means for controlling the flow of a liquid hydrocarbon fuel. Another purpose is the provision of magnetically operated controlling means for ensuring a quick operation of the valve controlling the flow of the liquid hydrocarbon fuel. Another object is the provision of thermostatic valve controlling means for use with said magnetic member. Other objects will appear from time to time in the course of the specification and claims.

I illustrate my invention more or less diagrammatically in the accompanying drawings wherein—

Figure 1 is a vertical section of my device with parts in elevation;

Figure 2 is a partial vertical section of my controlling device on an enlarged scale;

Figure 3 is an enlarged section along the line 3—3 of Figure 2;

Figure 4 is a section along the line 4—4 of Figure 2; and

Figure 5 is a section along the line 5—5 of Figure 2.

Like parts are indicated by like symbols throughout the specification and claims.

A generally indicates any suitable stove having for example the supporting legs A¹ and a bottom member A².

B is an outer cylindrical section resting upon the bottom member A². Resting upon the upper edge is the partition ring B¹ having the downwardly depending centering flange B² and the inner depending flange B³. B⁴ is a centering flange projecting from the upper face of the ring and adapted to position or center the cylindrical radiator member C which rests upon the ring.

Within the drum B is the mixing drum D, the upper edge of which engages the bottom of the partition member B¹ and is centered by the flange B³. It is herein shown as having a concave bottom D¹ in communication with the fuel inlet pipe D². The wall of the mixing drum D is penetrated by a plurality of air inlets D³.

In communication with the fuel inlet pipe D² and mounted thereon by means of the

screwthreaded portion D⁵ is the float chamber generally indicated as E.

Referring more particularly to the float chamber as shown in Figure 2, E¹ is the fuel supply line in communication with the initial admission chamber E² in which is positioned the strainer E³, yieldingly thrust upwardly by the spring E⁴ against the abutment E⁵. E⁶ is a screwthreaded removable plug which engages the spring E⁴ and which permits removal of the strainer E³ and access to the chamber E². E⁷ is a fuel passage extending upwardly from said fuel chamber and controlled by a valve member F. This valve member is pivoted to the end of the lever F¹, which in turn is pivoted as at F² closely adjacent its connection with the valve member F. Its opposite end is downwardly turned as at F³ and is secured to the float F⁴ in the float chamber E⁹. It will be understood that when the level of the oil in the float chamber is below the predetermined normal, oil flows through the passage E¹ and the passage E⁷ and escapes over the ledge E⁸ to the float chamber proper. F⁵ is a shield, associated with the valve F and adapted to prevent any substantial upward gush of the inflowing oil. At any predetermined level of the oil, the float, by means of its associated lever F¹, will close the valve F.

The fuel line D² is rigidly connected with the downward projection or boss G positioned on the side of the float chamber opposite to the inlet chamber E². It is provided with an aperture G¹ in opposition to the end of the line D², access to which may be had by removing the screw G². In communication with the space G¹ is a lateral duct G³ which in turn communicates with the vertical aperture G⁴. G⁵ is another vertical aperture directly in communication with the space G¹. Screw threaded in the apertures G⁴, G⁵ are the valve cylinders G⁶, G⁷ in the lower ends of which are screwthreaded the valve seats G⁸. The valve cylinders G⁶, G⁷ are apertured as at G⁹ to receive the oil passing through the circular screen members G¹⁰ which are held in position by tension springs G¹¹. Adjustment of the valve stem G¹² in relation with the valve seat

G⁸ is intended to be made by manual turning of the member G¹⁸.

H is a valve stem slideable in the bearing member H¹ which has the screwthreaded portion H² threaded into the upper end of the valve cylinder G⁷. Mounted upon the upper end of the valve stem H is the member H³. Upward movement of the stem H is limited by a flange or stop H⁴, adjustment of the valve

10 excursion being obtainable by rotation of the screwthreaded member H¹. The member H¹ has a flat bottom portion H⁵ which is in frictional engagement with one of the tension springs G¹¹, and an upwardly extending annular flange H⁶, slotted as at H⁷ to receive and

15 guide the ends J¹ of the magnet J. The magnet herein shown is in the form of a horseshoe, but any other suitable form may be employed.

20 K is an upwardly extending stem mounted upon the float chamber housing E, having one end K¹ bent to form a support for mounting any suitable thermostatic leaf K², herein shown as held in position by means of a bolt K³. K⁴ indicates an adjusting screw. Suspended on one end of the thermostatic leaf K² by any suitable means is the magnet J. The suspending means may consist for example of a screw K⁵ and nut K⁶ supporting a U-shaped strip K⁷ in which the magnet J is held by means of a pin K⁸.

25 It will be understood that when the leaf K bends to the dotted line position shown in Figure 5 in response to a drop in temperature, the ends J¹ J¹ of the magnet J will attract the member H³ associated with the valve stem H, thus lifting the valve stem from its seat G⁸ and allowing oil to flow to the fuel line D².

30 M generally indicates a housing which may be attached to the float chamber E by screws M¹⁰. I have shown the housing as having upwardly extending walls M¹ surrounding part of the float chamber and the upwardly projecting valve controlling apparatus, an outwardly extending portion M² covering the part of the exposed float chamber E⁹, and downwardly and inwardly inclined walls M³ and bottom enclosure M⁴, having associated therewith a horizontally extending shell or passage M⁵ of any suitable shape in communication with the drum B. The housing is open at the top, as at M⁶ to permit air to have free

35 access to the drum B, as shown by arrows in Figure 1.

40 It will be realized that whereas I have described and shown a practical and operative device nevertheless many changes might be made in size, shape, number and disposition of parts without departing from the spirit of my invention. I therefore wish my description and drawings to be taken as in a broad sense illustrative and diagrammatic rather than as limiting me to my specific showing.

The use and operation of my invention are as follows:

In the development of small portable or semi-portable or easily moved heating units for the burning of liquid hydrocarbons, such as used for heating rooms, garages and the like, I have found it practical to position the valve control means for controlling the flow of liquid hydrocarbons closely adjacent the burner or stove. It is essential in efficiently operating such burners to have a steady flow of liquid hydrocarbon enter the mixing chamber D, to procure a complete combustion for heating purposes.

45 I propose to adjust the manual operated valve stem G¹² in relation to its valve seat G⁸ to allow a sufficient amount of oil to enter the mixing chamber to support a small flame. To efficiently operate the main valve stem H controlling the main fuel supply, I employ magnetic means, the operation of which is as follows.

50 At a predetermined temperature the thermostatic control leaf K, adjusted by means of the screw K⁴, takes the position as shown in full lines in Figure 5. When the temperature drops, said thermostatic leaf K controlling the magnet J flexes to the position shown in dotted lines. The magnet will attract the disc H³ associated with the valve stem H, and thus will lift the valve stem from its seat and allow a predetermined flow of liquid hydrocarbons through the passages G⁵ G¹ and the pipe D² to the mixing chamber D. When the temperature rises the thermostatic leaf K will return to its original position, lifting the magnet. It will be understood that the valve stem will be held in such position until the spring action of the thermostatic leaf K will overcome the force of the magnet and pull away from the disc H³, thus dropping the valve stem and closing the valve seat. I have positioned the thermostatically operated controlling means within the air passage leading to the drum B, thus placing the thermostatic leaf spring in the direct path of the incoming air current.

55 It will be observed that the employment of the magnet, in association with the thermostatic leaf, provides a rapid opening and closing of the valve as contrasted to the relatively gradual regulation which is obtained by the employment of a thermostatic leaf alone. Thus when the leaf K² flexes downwardly toward the disc H³ on the valve stem H², at a certain point the force of the magnet will lift or snap the valve stem upwardly, completely opening the aperture G⁸. Similarly, when the leaf K² flexes back to its original horizontal position, the flange H⁴ prevents further upward movement of the valve stem, and the valve is finally dropped by the magnet, as the magnet is drawn away by the continued upward flexing of the leaf. It is of great advantage, in the operation of the

burner which only intermittently reaches its maximum, to avoid the intermediate stages of delivery of fuel. The present apparatus provides a predetermined minimum of fuel flow, 5 regulated by the valve stem G¹², and a maximum flow, controlled by the valve stem H, which is either fully opened or completely shut.

I claim:

10 1. In a fluid control valve, a valve seat, a valve and valve stem opposed thereto and means for withdrawing said valve from said seat, including a permanent magnet, and a thermostatic member associated with said magnet, and means for limiting the movement 15 of said valve from said valve seat in response to the force of said magnet.

20 2. In a control for liquid fuel, a fuel supply chamber, an outlet passage from said chamber and a valve seat associated therewith, a valve opposed to said valve seat, and means for lifting it therefrom, including a permanent magnet and a thermostatic member associated with said magnet, and means 25 for breaking the connection between valve and magnet at a predetermined point in the withdrawal of the magnet.

30 3. In a control for liquid fuel, a fuel supply chamber, an outlet passage from said chamber and a valve seat associated therewith, a valve opposed to said valve seat, and means for lifting it therefrom, including a permanent magnet adapted to be approached to said valve and means for approaching it thereto and withdrawing it therefrom, and guiding means for said magnet.

35 4. In a control for liquid fuel, a fuel supply chamber, an outlet passage from said chamber and a valve seat associated therewith, a valve opposed to said valve seat, a valve stem associated with said valve, a stop member on said valve stem and means for lifting said valve from said valve seat, including a permanent magnet and thermostatic member adapted to approach said magnet toward said valve stem and to withdraw it therefrom in response to fluctuations of temperature, said stop being positioned to break the connection between valve and 50 magnet at a predetermined point in the withdrawal of the magnet.

55 5. In combination with a hydrocarbon burner including a mixing chamber, a fuel line extending to said mixing chamber, a valve in said line and means for controlling it, including a permanent magnet and thermostatic means for approaching it to and withdrawing it from said valve, and an air passage surrounding said valve and extending to said burner.

60 6. In combination with a hydrocarbon burner including a mixing chamber, a fuel line extending to said mixing chamber, a valve in said line and means for controlling it, including a permanent magnet and ther-

mostatic means for approaching it to and withdrawing it from said valve, and an air passage, extending about said valve and fuel line, in communication with said burner.

7. In combination with a hydrocarbon burner including a mixing chamber, a fuel line extending to said mixing chamber, a valve in said line and means for controlling it, including a magnet and thermostatic means for approaching it to and withdrawing it from said valve, and an open-ended passage member, its upper portion in communication with the atmosphere, extending downwardly about said valve and in communication with said burner. 70 75

8. In combination with a hydrocarbon burner including a mixing chamber, a fuel line extending to said mixing chamber, a valve in said line and means for controlling it, including a magnet and thermostatic means for approaching it to and withdrawing it from said valve, said thermostatic means being in the line of air supply to said burner. 80 85

Signed at Chicago, county of Cook, and 90 State of Illinois, this 14th day of November, 1927.
